UNITED STATES PATENT OFFICE.

GEORGE A. BURNHAM, OF SAUGUS, MASSACHUSETTS, ASSIGNOR TO SEARS B. CONDIT, JR., OF BROOKLINE, MASSACHUSETTS.

ELECTRIC SWITCH.

1,409,997.

Specification of Letters Patent. Patented Mar. 21, 1922.

Application filed May 12, 1919. Serial No. 296,397.

To all whom it may concern:

Be it known that I, GEORGE A. BURNHAM, a citizen of the United States, a resident of Saugus, in the county of Essex and State of 5 Massachusetts, have invented an Improvement in Electric Switches, of which the following is a specification.

This invention relates to electric oil switches and has for its object to provide 10 means for increasing the current-carrying capacity of the switch by combining therewith an improved form of cooling means, and is intended as an improvement upon the device of my Patent No. 1,337,995, dated April 15 27, 1920.

Another object of this invention is to provide an electric switch with self-contained cooling means, which shall be simple and cheap in construction, and effective in operation.

A further object is to provide an electric switch with self-contained cooling means adapted for automatic operation by the current passing through the switch.

25 A further object is to provide a self-contained cooling means, made as an attachment and adapted to be applied to an electric switch by which the capacity of an existing switch may be increased.

30 The cooling means consists of an oil receptacle for the electric switch having heat radiators by which the radiating or heat dissipating surfaces are increased. The heat radiators may comprise oil conductors having heat radiating surfaces carried by the oil receptacle and in communication with the oil contained therein. Hot oil is adapted 35 to flow from the receptacle into the radiators to be cooled and from the radiators in cold condition to the receptacle to abstract heat

40 from the heated components of the switch. The oil receptacle and radiators are adapted to form a unit which may replace the oil receptacle of an existing switch and increase 45 its capacity by reducing the temperature rise of the switch.

A further object of the invention is the provision of means for the collection of carbon which is separated from the oil in which 50 the switch members are immersed and also for the collection and separation of moisture from the oil; and this object is attained by means of a settling chamber formed as a component of the oil circulatory system and

in which the solid particles and moisture 55 collect and are retained.

Fig. 1 is a partial side view of a multi-phase switching apparatus embodying my invention.

Fig. 2 is a vertical central section through 60 a switch of Fig. 1.

Fig. 3 is a section along lines 3—3 of Fig. 2.

Fig. 4 is a sectional detail of a modified form of my invention.

Fig. 5 is a side view of an oil receptacle 65 and radiators formed as a unit and detached from the switch.

Fig. 6 is a sectional view of an oil receptacle and radiator with the settling chamber incorporated with the receptacle. 70

Fig. 7 is a partial sectional view of an oil receptacle and radiator with the settling chamber incorporated with the radiator.

Fig. 8 is a front view of Fig. 7.

I have chosen the switch set forth in my 75 copending application filed June 17, 1918, Serial No. 240,317, for the purpose of illustrating my invention although it may be applied to other oil immersed switches.

As here shown, the switching apparatus 80 comprises the back-bone 10 from which the independent switches of the apparatus are suspended. Each switch comprises the switch frame 11, the stationary switch members 12 and movable switch members 13 depending from said frame. The oil receptacle 14, adapted to contain oil in which said switch members are immersed, is of usual box structure having walls of sheet iron or steel, and is removably secured to the switch frame 85 90 by means of the bolts 16 and wing-nuts 17, the removal of which permits the receptacle to be lowered from the switch frame for its removal.

A lining 18 of insulating material is arranged within the oil receptacle and as here shown is in actual contact with the walls thereof although in commercial manufacture it may be spaced a small distance therefrom, as a manufacturing expedient. Said linings, 100 usually, and as shown, extend above the level of oil in the receptacle, although switches and oil receptacles are constructed with linings which terminate beneath the oil level, the particular arrangement being a matter of 105 judgment on the part of the designer.

The heat radiators associated with the oil receptacle and as shown in Figs. 1 to 5 in-

clusive comprise the plurality of fluid conductors or pipes 20. Said pipes are formed, preferably, of material having high heat conductivity with surfaces of high heat dissipating ability and the dissipating ability may be enhanced by providing additional radiating surface, as by the discs 21, Fig. 4, which are spaced apart on the fluid conductors to insure unrestricted circulation of air therebetween, and are in good heat conducting union with said conductor.

Openings 25 are formed through the walls of the oil receptacle near the bottom thereof, and registering openings 26 are formed through the lining. Similar openings 27 and 28 are formed respectively in the receptacle and lining near the top thereof and below the level of oil in the receptacle for the purpose of providing fluid communication between the heat radiators or conductors 20 and the body of oil within the receptacle.

Said conductors are formed of single lengths of tubing reflexed at the end-portions, as at 20^a and 20^b and they are arranged substantially vertically and said end-portions are secured in fluid tight union with the walls of the receptacle, in register with the openings therein by welding, or other suitable means, whereby the hot oil may enter the radiators at the top through openings 27 and 28 and flow down the conductors, being cooled in its passage therethrough, and enter the oil receptacle through the openings 25 and 26 in the oil receptacle and lining to circulate upward within the oil receptacle and abstract heat from the heated components of the switch.

I prefer to arrange my heat radiators on the ends of the oil receptacle whereby the switches may be spaced closely together and thereby occupy less space than could otherwise be the case. Such an arrangement is also preferable when the oil receptacle with heat radiators is to replace the oil receptacle of a switch having no provision for its cooling as the exchange of receptacles may be accomplished without in any way altering the spacing of the switch unit in a multi-phase switching arrangement. Furthermore, a more efficient heat-dissipating arrangement obtains inasmuch as there is an unimpeded circulation of air about the surfaces of the radiator and there is no interference between radiators of adjacent switches of a switching apparatus.

In Fig. 4 I have illustrated the cooled oil as entering the receptacle from the radiator through the bottom thereof whereby it may be directed in a more efficient manner over the switch members to abstract heat therefrom. A rather greater heat-dissipating surface of the radiator may also result from this arrangement.

Although I have here shown the heat radiators as comprising a plurality of fluid

conductors having heat-radiating surfaces and each independently connected with the oil receptacle yet it is obvious that other well known forms and arrangements of radiators may be utilized, when desired. 70

The circulation of oil in the oil receptacle and heat radiators depends upon the difference in specific gravity of hot and cool oil. The hot and light oil rises to the surface in the receptacle and flows into the radiators 75 where it becomes cooled. The cold oil has greater density than the hot oil and consequently flows downward in the radiators and enters the bottom of the oil receptacle in cooler condition. 80

The oil in the oil receptacle gradually carbonizes, with repeated switch operation, and the separated carbon gradually settles and collects in the bottom of the oil receptacle. The separated and precipitated carbon does not particularly effect the operation of the switch in interrupting a circuit in that type of switch having no provision for the active circulation of oil for its cooling, when the period between consecutive operations 90 of the switch is sufficiently extended to permit the settling of the carbon stirred up at each operation. In switches having provision for the active circulation of the oil within the oil receptacle, for the forced cooling of the switch, the rate of flow of the oil may be so great as to entrain the particles of carbon and prevent settling thereof and the insulating properties may thereby become impaired. For this reason it is desirable to provide means to collect the carbon particles to thereby prevent impairment of the insulating properties of the oil which may result from the circulation of such carbon particles. 100

This result may be accomplished by providing a settling chamber for the carbon particles, in which the velocity of the oil, in its circulation, is so low that the carbon particles fall by their weight and collect in 110 the chamber. Moisture also gradually collects in the oil and may also be separated therefrom by settling in said chamber. 105

In Fig. 6 I have formed the settling chamber as a component part of the oil receptacle 115 itself. The discharge pipe 20 of the heat radiator enters the oil receptacle at a suitable height above the bottom thereof whereby a quiescent body of oil is provided, between the entrance of oil from the radiator and the bottom of the tank, as at 31, in which the separated carbon particles are precipitated and retained as a sludge. Each switch operation may stir up the sludge but it will soon collect in the bottom of the settling chamber, 125 and only clear oil will then be circulated through the receptacle and heat radiators.

In Figs. 7 and 8 I have shown a settling chamber associated with the heat radiator.

The heat radiator here shown comprises 130

an intake manifold 40 and a discharge manifold 41, each having a volume sufficient to properly distribute the oil to the oil conductors of the radiator for its cooling. A plurality of pipes or conductors 42 are extended between said manifolds and have a combined heat dissipating surface sufficient to dissipate the heat generated in the switch components. The intake manifold is connected by the intake pipe 44 to the receptacle which communicates therewith beneath the surface of the oil in the oil receptacle and the discharge manifold is connected with the oil receptacle through the discharge pipe 45 which, in this construction, may communicate with the oil receptacle at the bottom thereof. Couplings 46 form a component part of said intake and discharge pipes whereby the radiator may be conveniently removed from the receptacle.

The sludge settling chamber is here formed as a component part of the discharge manifold. The side walls 41^a thereof extend a substantial distance below the connection of the discharge pipe therewith and the bottom wall 41^b tapers toward the center of the manifold to a sludge outlet 47 which is closed by the removable plug 48. The chamber thus formed below the outlet from the discharge manifold forms a compartment in which the carbon particles in the oil circulated through the radiator may settle and the oil in the receptacle may thereby remain free from carbon. With this form a second switch operation may occur immediately after the first operation and yet the second operation is just as effective in interrupting the circuit as the first operation.

When the sludge has collected in a sufficient quantity it may be removed by removing the plug 48 from the opening 47, and the oil also drawn off may be replaced by fresh oil introduced into the system through the filler neck 50 in the top of the intake manifold.

I claim:

1. An electric switch comprising, the combination of stationary and movable switch members, a receptacle adapted to contain oil in which said members are immersed and one or more fluid conductors arranged at the outside of said receptacle and exposed to a cooling temperature which are in open communication with said receptacle near the top and bottom thereof and below the oil level therein for the thermal circulation of the fluid contained in the receptacle, and dissipation of the heat contents thereof.

2. As a new article of manufacture, an electric switch having a tank adapted to contain oil in which the switch components are immersed and heat radiators comprising one or more isolated fluid conductors carried by said tank arranged in open communication with said tank at the upper and lower ends

thereof and below the oil level therein for establishing thermal circulation of the contents of the tank.

3. As a new article of manufacture, an electric switch having a tank adapted to contain oil in which the switch components are immersed and heat radiators comprising a plurality of fluid conductors connected with said tank at the upper and lower ends thereof and below the oil level therein and extending into a reducing temperature for the thermal circulation of the fluid by which the heat from the tank is carried away.

4. An electric switch comprising the combination of a switch frame, stationary and movable switch members carried thereby, an oil receptacle adapted to contain oil in which said members are immersed, means to removably secure said receptacle to said switch frame, oil cooling pipes carried by said receptacle on the outside thereof having an inlet near the top of the receptacle and below the oil level therein for the passage of hot oil from the receptacle to said cooling pipe, and having an outlet near the bottom of the receptacle for cooled oil from the cooling pipes to the receptacle by which to establish a thermal circulation of, and cool, the contents of the receptacle.

5. The combination, in an electric switch, of an oil receptacle adapted to contain oil in which switch components are immersed, and heat radiators carried by the receptacle on the outside thereof having means for establishing open communication with the oil space within the receptacle.

6. An electric switch comprising the combination of a switch frame, movable and stationary switch members carried thereby, an oil receptacle adapted to contain oil in which said switch members are immersed, heat radiators carried by said receptacle on the outside thereof, having means for establishing fluid communication between said radiators and the interior of said oil receptacle, and means to removably secure said oil receptacle with associated radiators to the switch frame.

7. An attachment for electric switches comprising an oil receptacle adapted to contain oil in which switch components are immersed, heat radiators carried by said receptacle on the outside thereof, in open communication with the interior of said receptacle, and means to removably secure the attachment to an electric switch.

8. An electric switch comprising the combination of stationary and movable switch members, a receptacle adapted to contain oil in which the switch members are immersed characterized by having side-walls and end-walls, and heat-radiators carried by the receptacle on the outside at its end-walls in open communication with the oil space in the receptacle.

9. An attachment for electric switches comprising a receptacle adapted to contain oil in which the switch members are immersed characterized by having side-walls and end-walls, and heat-radiators carried by the receptacle on the outside at its end-walls in open communication with the oil space in the receptacle. 60
10. An electric switch comprising movable and stationary switch members, a receptacle adapted to contain oil in which the switch members are immersed, a lining of insulating material disposed within the receptacle at the side walls thereof, a plurality of vertically disposed radiator pipes carried by the receptacle on the outside, and said side walls and lining of said receptacle having a plurality of registering openings to establish open communication between 20 said radiator pipes and the oil space of said receptacle. 65
11. An electric switch comprising movable and stationary switch members, a receptacle adapted to contain oil in which the switch members are immersed, a lining of insulating material disposed within the receptacle adjacent the walls thereof, heat radiators carried by said receptacle on the outside thereof and the side-walls and lining of 30 said receptacle having registering openings to establish open communication between said radiators and the oil space in the receptacle. 70
12. An oil receptacle for electrical apparatus having a heat radiator carried on the outside thereof, an insulating lining disposed within it adjacent its side wall and registering openings in its side wall and lining to establish open communication between the radiator and the oil space of the receptacle. 75
13. An attachment for electric switches comprising an oil receptacle adapted to contain oil in which switch components are immersed, a lining of insulating material disposed within said receptacle and adjacent the walls thereof, heat radiators carried by 45 said receptacle on the outside thereof, said oil receptacle having openings through its walls and lining to establish open communication between said radiators and the interior of said receptacle, and means to secure the attachment to an electric switch. 80
14. An electric switch comprising stationary and movable switch members, an oil re- 55
- ceptacle adapted to contain oil in which said members are immersed, a cooling circulatory system for the oil including heat radiators carried by said receptacle, and a settling chamber connected with said oil circulatory system. 85
15. An electric switch comprising stationary and movable switch members, an oil receptacle adapted to contain oil in which said members are immersed, a cooling circulatory system for the oil including heat radiators carried by said receptacle, and a settling chamber connected with said oil circulatory system and means to removably secure said oil receptacle with associated element to the switch. 90
16. An attachment for electric switches comprising an oil receptacle adapted to contain oil in which switch components are immersed, an oil circulatory and cooling system associated with and carried by said receptacle, a settling chamber connected with said circulatory system, and means to removably secure said attachment to an electric switch. 95
17. In an electric switch comprising stationary and movable switch members, and an oil receptacle adapted to contain oil in which said members are immersed, a circulatory and cooling system for the oil in said receptacle whereby the switch is cooled, a heat radiator forming a component of said circulatory system carried by said receptacle on the outside thereof, and a settling chamber connected with said radiator. 100
18. In an electric switch comprising stationary and movable switch members, and an oil receptacle adapted to contain oil in which said members are immersed, a circulatory and cooling system for the oil in said receptacle whereby the switch is cooled, a heat radiator forming a component of said circulatory system carried by said receptacle on the outside thereof, and a settling chamber included in said circulatory system external the oil receptacle to remove solid particles from the circulated oil. 105
